UNITED STATES PATENT OFFICE.

MILES E. BAILEY, OF WASHINGTON, DISTRICT OF COLUMBIA.

ELECTRIC RAILWAY.

No. 833,017.

Specification of Letters Patent.

Patented Oct. 9, 1906.

Application filed May 27, 1905. Serial No. 262,645.

To all whom it may concern:

Be it known that I, MILES E. BAILEY, a citizen of the United States, residing at Washington, in the District of Columbia, have invented certain new and useful Improvements in Electric Railways, of which the following is a specification.

My invention is designed as an improvement in miniature electrical rails, one object being to provide a mechanism of this description suitable for to's or window-displays wherein the train or car being placed on a straight track as distinguished from a circular track will automatically reverse itself.

15 A further object is the provision of mechanism of this nature wherein the main track is provided with a siding, each end of which siding is connected to the main track or line, and means for automatically connecting and disconnecting the siding with a suitable electrical current whereby a car on the siding may be left "dead" or cut in to cause it to remain on the siding or to move off the siding, respectively.

25 My invention further consists in the provision of a main track and a siding communicating at each end with the main line, in combination with a car or train on the main line and means for reversing the direction of 30 movement of the car or train, a car or train on the siding, and means operated by the two cars or trains for cutting the siding in and out, the cars or trains alternately designed to take the siding automatically.

35 In carrying out my invention I provide certain novel details of construction and combinations of parts, such as will be more fully set forth hereinafter and particularly pointed out in the claims.

40 In the accompanying drawings, Figure 1 is a plan view of the track and siding. Fig. 2 is a detail perspective view of one of the reversing or track devices. Fig. 3 is a detail perspective view of the means for cutting the siding in and out. Fig. 4 is a perspective view of the car device, and Fig. 5 is a view in side elevation of the same.

In the drawings, A indicates the main line, comprising rails 1 and 2, and B the siding. 50 The rails of track A are each connected with separate terminals of a source of electrical energy in any suitable manner (not shown) and constitute the live rails.

The siding consists of two rails 3 and 4, lying parallel with the main line, although this is not essential, as the siding may be curved,

if desired. At the points where the siding joins the main track the rail 2 of the main line adjacent the siding is broken, as at 5 6 and 7 8, for the purpose of breaking the circuit and preventing the energization of the siding through a car on the main line as it passes across the juncture of the siding with the main track. Sections 9 and 10 constitute continuations of the main-line rail 2 65 and extend or span the space between the lead rails of the siding at each end of junction-point thereof with the main line, said sections 9 and 10 being spaced apart from the remainder of the rail 2, such spaces serving as 70 insulation. The rail 2, therefore, adjacent the siding consists of three separate pieces—the sections 9 and 10 and the connecting-rail 11, extending between the sections 9 and 10—the rail 2 thus having four insulating-spaces 75 formed therein, the rail 11 being out of contact or spaced apart from the adjacent ends of the sections 9 and 10, but electrically connected to rail 2, as shown in Fig. 1. If desired, the sections 9, 10, and 11 may be connected to rail 2 by switch-plates; but as this would increase the cost of manufacture the illustrated form is preferred. The siding proper consists of the rails 3 and 4. At the ends of the outer rail 3 are located the outer 80 lead-rails 12 12, which may be virtually continuations of the main-line rail 2, being bent or offset from the main-line rail and having their free ends in alinement, but out of contact with or spaced apart from the opposite 85 ends of the outer siding-rail 3.

At one end of the siding a stationary inner lead-rail 13 is secured across the main-line track, one end lying adjacent to but out of contact with the adjacent ends of sections 9 95 and 11, the opposite end of lead-rail 13 lying close to but out of contact with the main-line rail 1, the ends of the lead-rail 13 being just far enough away from the main-line rails to permit the passage of the wheel-flanges 100 therebetween. A similar inner lead-rail 14 is located at the opposite end of the siding; but this latter rail also consists in part of a pivoted track-switch 15, the free end of which is normally held against the inner face of the main-track rail 1 by means of a slight spring or other suitable yielding member. (Not shown.) The inner lead-rails of course communicate with but are spaced apart from the inner rail 4 of the siding. It may also be 110 proper to mention at this point that if the siding is arranged to lie parallel with and adja-

- cent to the main line the ties 16 16 may be extended so as to support the siding-rails, as well as the main-line rails, in the manner shown. The ties are of course formed of wood or insulated from the rails in any suitable manner, and it will be understood that though my device as shown is constructed for an amusement or entertainment, yet it may be capable of use in other lines as well.
- 10 Located, preferably, at a point between the main-line rails 1 and 2 and between the opposite ends of the siding, although this location is not absolutely essential, is a switch-box 17, having a contact-point 18 thereon connected to one of the siding-rails, as 4, by any suitable means, as a wire, for instance, the rail 3 of the siding and the connecting-rail 11 of rail 2 being connected by means of a wire 19, and pivotally mounted on the switch-box 17 is a switch-arm 20, connected with the live rail 1 of the main line and adapted to engage the contact 18, whereby a circuit is formed from rail 1 through the arm to the contact-point, thence to rail 4 of the siding, thence 25 through a car on the siding to rail 3, and thence back to member 11 of rail 2, which member is separately connected with the electrical source. The outer free end of the arm is connected, by means of a rod 21, to a lever 22, journaled on the side of one of the ties 16 near the stationary inner lead-rail 13, the ends of the lever being cranked, as shown at 23 and 24, cranked end 23 lying adjacent the outer lead-rail 12 and crank 24 located at 30 a point intermediate the main-line rails 1 and 2, where it will be out of the way of cars passing in either direction. In fact, the crank 24 is for the purpose of preventing endwise movement of the lever in one direction and to 35 afford a means for pivotally fastening the connecting-rod thereto. The connecting-rod 21 is also extended in the opposite direction past the switch-arm 20, where it is likewise pivotally secured to a member 25, pivotally supported on the side of one of the ties 16 and located adjacent rail 2 or section 11 thereof, as may be, and within the road-bed between the rails 1 and 2 at a point near the track or lead switch 15.
- 40 From the foregoing it will be seen that a car moving in the direction of the arrow *a* will engage the member 25 and move the arm 20 into engagement with its contact 18 to complete a circuit through the siding-rails 3 and 4, thus energizing a car on the siding, which latter car in passing off the siding in the direction of the arrow *b* will throw the lever 22 down by means of the engagement of a projection 32 on the car with crank 22, there- 45 by cutting out the siding-circuit.
- 50 Located near opposite ends of the main line A and adjacent the live rail 1, but inside the road-bed, are the track devices 26 26, each of which consists of a plate suitably pivoted within a guiding-boxing 26', secured to

the side of the respective ties and normally held in raised position by means of a light spring 27 or other yielding means having but sufficient strength to return the plate to upright position after it has been forced down. 70 These plates by reason of their positions relative to the ties are adapted to yield in but one direction, and when the car is proceeding toward the end of the main line the plates remain in upright position to operate the car 75 device presently to be described and actuate the latter to reverse the car.

Each car C is provided with a motor (not shown) deriving its electrical energy from the rails, the direction of rotation of the motor-armature being governed by a controller, which may be constructed in any suitable manner, the shaft 28 of the controller being extended downward through the controller-box to a point beneath the bottom of the car 80 and then bent or turned outwardly at right angles, as at 29. A trip 30 is pivotally and loosely secured at its upper end to one side of the motor-frame, the free end of which trip depends to a point adjacent the level of the 85 ties and in alignment with the track devices 26, so that as the car approaches one of the track devices near the end of the main line the lower end of the trip will engage such track device and be moved or swung positively in a rearward direction, and as the car proceeds the trip will move away from the track device and when entirely released therefrom will, by reason of its own weight and its loose connection with the controller-shaft, fall back or downward a slight distance without reversing the controller, the right-angled extension 29 being loosely and pivotally connected to the trip at a point intermediate its length by means of a bar 31. The provision for permitting the partial return of the trip after its engagement with the track device is to enable the trip to engage the track device at the opposite end of the main line. This trip is located on that side of the 90 car adjacent the rail 1, and depending from the motor-frame on the opposite side of the car or adjacent rail 2 is a projection 32, adapted to operate the pivotally-supported member 25. 100

Having thus fully described my invention, a brief description of its operation follows. Hitherto, so far as I am aware, it has been unknown in toy railways, either mechanically or electrically operated, to provide a straight track and means for automatically reversing the direction of movement of the car thereon. Instead a circular track has been provided upon which a car or train continuously travels in one direction only. When the 105 motive power is electricity, such continuous travel consumes a very large amount of electricity and is a source of considerable expense. In order to avoid so great an expense and at the same time to provide a 110

novel and easily-constructed device, I have produced the invention heretofore set forth. A car or train is first placed on the siding, the arm 20 being out of engagement with the contact 18, thereby cutting out the siding-circuit. A car or train is then placed at that end of the main line marked D, care being taken to place the controller in the correct position to supply current to the motor to drive the car in the direction desired. If the car is placed between the switch and the track device 26, the controller may be at either limit of its movement, being set by means of the handle on top of the controller-box, stops being provided to limit such movement of the controller-shaft; but if the car is placed on the extreme end of the main line behind the track device the controller should be set in the position necessary to cause the car to move toward the opposite end of the line. Power being communicated to the rails, the car on the main line will move toward the siding and over the section 9, thence along section 11, and when the car arrives over the pivotally-supported member 25 the stationary projection 32 on the car will strike such member and through the connecting-rod 21 will move the arm 20 into engagement with its contact-point 18, thereby cutting in the siding-circuit and simultaneously through the continuation of the rod moving the lever 22 to raise the crank 23. The rail-section 11 will remain energized at all times and the siding will remain energized until the siding-car throws the lever 22 to break the circuit. The car on the main track then forces aside the yielding track-switch 15 and passes onto the end of the main line, the adjacent ends of the sections 9, 10, and 11 being sufficiently close to each other to permit the wheels to run thereon and to take the rails without mishap, the yielding switch snapping back into place against the live rail 1 as soon as the car has passed. As the car nears the end of the main line the trip 30 engages the track device and automatically reverses the controller, which is frictionally held in such reversed or set position, as usual. A slight amount of lost motion is provided to permit the trip to drop down a short distance after passing the track device, as before set forth, the car continuing some distance on the main line in the same direction owing to its impetus. As soon as the force of the motor overcomes the impetus of the car the latter moves backward along the main line, the trip 30 engaging and bending the adjacent track device downward in its passage thereover; but when the car reaches the track-switch 15 the car is shunted onto the siding along the lead-rails and switch under its own impetus, since simultaneously with the completion of the circuit through the siding, as heretofore set forth, the car originally placed thereon is energized, and its controller having been previously set the car moves in the direction of the arrow b and, reaching the crank 23, throws the lever 22 down and moves the arm 20 away from its contact 18, cutting out the siding. The siding-car, however, under its own impetus passes onto the main line and, catching the circuit again, travels to the end of the main line, where the controller is automatically reversed and the car returned along the main line throughout its length. The movement of the main-line car over the member 25 cuts in the siding and energizes the car switched thereupon to cause it to pass off the siding in the direction of the arrow b, the impetus of the car having taken it onto the rails 3 4 of the siding from the switch. This movement of the two cars or trains is continued as long as the track-circuit remains energized, the car alternately taking the siding and becoming dead until the siding-circuit is again energized by the returning car.

It will be seen that the ends of sections 9 and 10 of rail 2 approach the adjacent ends of rail 2 and siding-rail 4 so closely as to just permit the passage of a wheel-flange freely therebetween, and, further, the track devices 26 and the member 25 are placed on opposite sides of the track, although not necessarily between the rails 1 and 2, so that the projection 32 will not engage the track devices nor trip engage the member 25.

The mechanism is also adapted to be used with an overhead or underground circuit instead of with the track-circuit shown and is capable of other uses than for amusement. Indeed its principles may be applied with but little change to all or nearly all power-operated traveling devices which move on tracks or on a certain defined pathway. It will also be noted that many changes might be made in the forms and arrangement of the member 25 and its connected parts, the track devices 26, and the car devices, as well as in other parts of my device, without departing from the spirit and scope of my invention, and hence I do not wish to limit myself to the exact construction herein set forth; but, Having thus fully disclosed my invention, what I claim as new, and desire to secure by Letters Patent, is—

1. An automatic electric-railway system comprising cars, a main line and a siding insulated therefrom and communicating therewith, means for cutting the siding in and out of circuit with the main line, a movable member on one side of the main line controlling the actuation of the circuit-controlling means, track devices located on the opposite side of the main line, and means located on opposite sides of the car adapted to operate the movable member and to be operated by the track devices respectively.
2. In an automatic electric-railway sys-

- 4
5. The combination with a main line, of a siding insulated therefrom and communicating therewith, means connecting the siding with a source of electrical supply, a make-and-break device interposed in said means, a car-operated lever journaled near one end of the siding, a car-operated movable member located near the opposite end of the siding, means connecting the lever, the movable member and the make-and-break device, and means for shunting a car onto the siding. 55
6. In an automatic railway system, the combination with an energized main line, of a siding insulated therefrom and communicating therewith, a car-operated cranked lever journaled near one end of the siding, a car-operated member located near the opposite end of the siding, means for electrically connecting the siding and main line, a make-and-break device interposed in the last-named means, means connecting the cranked lever, the member and the make-and-break device, and means for automatically shunting a car onto the siding. 65
7. The combination, in an automatic electric railway, of a normally energized main line, a siding insulated therefrom and communicating therewith, a switch-arm normally connected with one rail of the main line, a contact-point adapted to be engaged by the switch, means connecting the contact-point and one rail of the siding, means connecting the remaining siding and main-line rails, and car-operated means located near each end of the siding and connected to the switch-arm. 70
8. The combination in an automatic electric railway, of a normally energized main line, the ends of which are separated from each other, a siding insulated from and communicating with the main line, cars adapted to operate on said siding and main line, car-operated means for cutting the siding into and out of circuit with the main line, controller-shafts on the cars, a lateral extension carried by the shafts, trips pivotally mounted on the cars, means connecting the trips and extensions and track devices engaged by the trips to reverse the controller-shafts. 75
9. The combination in a railway, with a car and a track on which it runs, of a track device, a controller-shaft on the car, a trip loosely mounted on the car, and means connecting the trip and shaft, the trip engaged by the track device to reverse the controller-shaft, the connection between the trip and shaft being loose to permit a slight amount of lost motion to allow the trip to partially return to its lowest position automatically after its engagement with the track device. 80
40. In testimony whereof I have signed my name hereto in the presence of two subscribing witnesses.
45. In an automatic electric-railway system, the combination with a main line, of a siding insulated therefrom and communicating therewith, means connecting the siding with a source of electrical supply, a make-and-break device interposed in said means, a car-operated lever journaled near one end of the siding, a car-operated movable member located near the opposite end of the siding, and means connecting the lever, the movable member and the make-and-break device. 90
50. In an automatic electric-railway system, the combination with an energized main line, of a siding insulated therefrom and communicating therewith, a car-operated
